UNITED STATES PATENT OFFICE

DAVID E. DEVOL, OF GRAND BAY, ALABAMA.

ATTACHMENT FOR SHOTGUNS.

966,889.

Specification of Letters Patent.

Patented Aug. 9, 1910.

Application filed March 23, 1910. Serial No. 551,047.

To all whom it may concern:

Be it known that I, DAVID E. DEVOL, a citizen of the United States of America, residing at Grand Bay, in the county of 5 Mobile and State of Alabama, have invented new and useful Improvements in Attachments for Shotguns, of which the following is a specification.

This invention relates to attachments for 10 shot guns or similar fire arms, and has for an object to provide an attachment which may be conveniently engaged with the muzzle of the gun and which will be so constructed as to act as a spreader for the shot 15 after they are finally discharged from the barrel.

In the drawing, forming a portion of this specification and in which like numerals of reference indicate similar parts in the several views:—Figure 1 is a side elevation of 20 a portion of a barrel showing my improved shot spreader applied thereto. Fig. 2 is a detail perspective view of the spreader. Fig. 3 is a transverse section taken on the 25 line 3—3 of Fig. 1.

With reference to the drawing, it will be seen that my improved attachment consists 30 preferably of a spring member 1 which is substantially of semi-cylindrical form in cross section to conform in configuration with the shape of the muzzle end of the barrel B shown in Figs. 1 and 3 of the drawing. By constructing the member 1 of spring metal the side portions thereof will be more 35 or less elastic and when the member is engaged with the barrel the said side portions will yieldingly grip corresponding surfaces of the barrel to hold the member thereon, as is obvious.

40 The forward extremity of the member 1 is formed to provide forwardly extending arms 2 which extend beyond the muzzle of the barrel, as shown. These arms are bent or formed otherwise in an obvious or like manner to provide inwardly directed vanes 3. These vanes are formed to provide relatively sharp edges 4, as shown. The vanes 3

are each bent preferably on a diagonal line from the main body portion of its arm so that the distance between the vanes at the 50 rear ends of the arms will be greater than the distance between the vanes at the forward extremities of the arms.

The construction of the attachment herein set forth and described is such that it can be 55 quickly and conveniently applied to any gun barrel or the like and, incident to the provision of the vanes 3 which extend immediately in line with the bore of the barrel, the shot will be spread after their final discharge in a very effective manner.

I claim:—

1. A shot spreader for guns comprising a split member gripping the muzzle end of the barrel and formed to provide forwardly extending shot-spreading vanes whose inner edges are flared downwardly toward the muzzle end of the gun and sharpened throughout.

2. A shot spreader for fire arm barrels 70 comprising a member removably fitting the outer end of the barrel and formed beyond the end of the barrel to provide vanes which are arranged in intersecting planes, the said vanes having their outer edge portions extending directly into the main body portion 75 of the said member to present angularly extending surfaces.

3. A shot-spreading attachment for fire arm barrels comprising a member removably fitted to the outer end of the barrel and formed with integral vanes which are arranged in intersecting planes and which are positioned immediately in front of the bore of the barrel, each vane having its inner 85 edge flared outwardly and rearwardly toward the outer end of the barrel and sharpened throughout.

In testimony whereof I affix my signature in presence of two witnesses.

DAVID E. DEVOL.
